United States Patent

Des. 237,903
Patented Dec. 2, 1975

237,903

COMBINED SPECTACLE TEMPLE AND HEARING AID OR SIMILAR ARTICLE

Vittorio Giannetti, Rome Via Deruta 63, Rome, Italy

Filed Mar. 11, 1974, Ser. No. 449,853

Term of patent 14 years

Int. Cl. D16—06; D24—99

U.S. Cl. D57—1 A

FIG. 1 is a perspective view of a combined spectacle temple and hearing aid of my new design, the inner side being shown.

FIG. 2 is a top plan view thereof;

FIG. 3 is a bottom plan view thereof; and

FIG. 4 is an outer side elevational view of the design shown in FIGS. 1 to 3.

I claim:

The ornamental design for a combined spectacle temple and hearing aid or similar article, substantially as shown.
